R. J. PATTERSON.
STEAM ENGINE CONTROLLER.

(Application filed Oct. 4, 1900.)

(No Model.)

UNITED STATES PATENT OFFICE.

RALPH J. PATTERSON, OF WOBURN, MASSACHUSETTS.

STEAM-ENGINE CONTROLLER.

SPECIFICATION forming part of Letters Patent No. 680,172, dated August 6, 1901.

Application filed October 4, 1900. Serial No. 31,953. (No model.)

To all whom it may concern:

Be it known that I, RALPH J. PATTERSON, a citizen of the United States, and a resident of Woburn, county of Middlesex, State of Massachusetts, have invented an Improvement in Steam-Engine Controllers, of which the following description, in connection with the accompanying drawings, is a specification, like characters on the drawings representing like parts.

This invention relates to steam-engine controllers; and it has for its object to provide a mechanism wherein very slight variations in the speed of the engine will influence the cut-off for the cylinder, so that the engine will be more sensitive and will respond more quickly to changes in load than engines as ordinarily built.

In most engines now in use the speed of the engine is controlled by some form of centrifugal governor which is directly connected to the valve-gear, such governor operating as the speed of the engine varies through the said connections to vary the cut-off for the cylinder, so that when the engine increases its speed the cut-off will be shortened and when the speed of the engine slackens the cut-off will be correspondingly lengthened to admit more steam to the cylinder. One objection to engines constructed as above is that the centrifugal governor must be heavy enough to operate the parts connecting the same with the cut-off. It is obvious that a heavy governor will not respond as quickly to any changes in load as a lighter governor and will not therefore control the speed of the engine as accurately as such lighter governor would; but heretofore it has been impossible to use an extremely light and sensitive governor, because such a governor would not be heavy enough to operate the connections between it and the cut-off.

In my present invention I overcome the above-noted objections by providing a suitable pressure-chamber and utilizing the variations in pressure in said chamber to control the cut-off for the cylinder, the variations in pressure in the said chamber being controlled by the speed of the engine. One convenient way of accomplishing this is to control a valve leading to the said pressure-chamber by means of a suitable centrifugal

governor which is operated by the engine in the usual way, and such ball-governor can be made very light and will be correspondingly sensitive, so that variations in the pressure in said pressure-chamber will occur exactly as the speed of the engine varies, such variations in pressure operating mechanism which in turn controls the cut-off.

One embodiment of my invention is illustrated in the drawings forming a part of this application, in which—

Figure 1 is a view showing one form of mechanism. Fig. 2 is a view showing a slightly-modified construction. Fig. 3 is an enlarged detail showing one form of valve, and Fig. 4 is a detail showing the slotted link on an enlarged scale.

My invention may be applied to various types of engines; but as illustrating one convenient application thereof I have shown diagrammatically in the drawings part of an engine of the Corliss type, C representing the cylinder and v representing the inlet-valves, the exhaust-valves being represented by e. Herein the cylinder and valves are illustrated diagrammatically only, for as they are of any familiar Corliss type it is not deemed necessary to show the oscillating disk and connections by which the valves are opened and closed, they forming no part of my present invention. The inlet-valves v are controlled as to the time of their cut-off by the rods r, which are connected to opposite ends of a fulcrum-lever l, as is usual in this class of device, the said lever l, as illustrated in Fig. 1, being connected to the slotted link 3 by means of the connection c and the link being pivotally mounted upon any suitable stationary point, it being illustrated in the drawings as mounted at 4 upon the standard which supports the governor g; but I wish it understood that this particular arrangement is not essential.

Instead of connecting the link 3 directly with the governor g, as in most engines of this class, I provide mechanism whereby the said link is operated by variations in pressure in a suitable pressure-chamber, such variations in turn being caused by mechanism controlled by the speed of the engine. The pressure-chamber p may be of any suitable kind, although I prefer to make it in the

form shown—*i. e.*, what is known as a piston-pot, wherein the casing is made in two parts bolted together and having clamped between them a suitable diaphragm, one side of which 5 is connected to the operating mechanism which controls the link 3 and the other side of which is subjected to the pressure in the pipe 13, which in this instance is steam-pressure. The steam-pressure in the pressure-chamber 10 is controlled by a suitable valve device (represented generally by 14) which is situated in an exhaust-pipe 15, connected to the pressure-chamber and leading to some point of much lower pressure than the pressure 15 in pipe 13, which may be connected to any suitable source of pressure-supply and communicates with the pressure-chamber. If the pipe 13 is connected to the boiler, then the pipe 15 would preferably connect with the 20 receiver if the controller were used in connection with a multiple-cylinder engine or with the atmosphere if used to control a single-cylinder engine, and if the pipe 13 should be connected with the receiver the pipe 15 would 25 of course lead to the atmosphere or the condenser, as circumstances dictated. By throttling the opening through said valve 14 the pressure in the pressure-chamber can be varied, and by the mechanism described such 30 variations operate to control the cut-off.

In this embodiment of my invention the operation of the valve 14 is made automatic by operating the same by any suitable centrifugal governor, whereby as the speed of 35 the engine increases the valve is opened wider and the pressure in the pressure-chamber correspondingly decreased, such decrease in pressure operating to shorten the cut-off, and as the engine slackens its speed the valve is 40 correspondingly closed to thereby increase the pressure in the chamber, and hence lengthen the cut-off.

g represents the governor, which may be of any type, that shown being the familiar "ball-governor," it being of usual construction, except that it is comparatively small and is therefore more sensitive than a heavier governor would be. The said governor has the usual arm 17 projecting therefrom, which is connected by means of rod 18 to the lever 19, which in turn is connected to the valve-stem 20, the said lever preferably being pivotally mounted on an arm 21 on the valve-easing.

Any suitable valve 14 may be used; but I 55 have found that good results flow from the use of a double-ported throttle-valve, such as is illustrated in Fig. 3, in which 22 is the inlet and 23 the outlet, the valve-body 24 being fitted to and seating on the two seats 25 and 60 26 when the valve is closed. One advantage of this type of valve is that it is a balanced valve and can therefore be operated by a comparatively small force.

As illustrated in the drawings, the exhaust-pipe 15 is much larger than the inlet-pipe 13, thus allowing the steam to freely exhaust when the valve is opened or partially opened.

As herein illustrated, the diaphragm in the pressure-chamber *p* has connected thereto at one side the plunger or piston-rod 5, pivotally connected to the lever 6, said lever being pivotally mounted in any suitable way, preferably upon an arm 7 upon the diaphragm-easing, and carrying at one end the weights *w*. A second lever 8 is pivotally mounted upon a suitable stand 9, the said lever carrying at one end a roll 10, which plays in the cam-slot 11 in the link 3, as shown in the drawings, the opposite end of the lever 8 being connected by any suitable mechanism with the lever 6. The pipe 13, communicating with the source of steam-supply, which may be either the boiler or receiver, leads into the pressure-chamber *p*, as stated above, whereby the diaphragm is constantly subject to the steam-pressure.

With this construction of device the operation will be as follows: As the speed of the engine increases the balls of the ball-governor will fly outward and will thereby raise 90 the arm 17 in a well-known manner, the arm through the connection described operating to open the valve, and thereby reduce the pressure in the pressure-chamber *p*. The weights *w*, which are attached to the end of 95 the arm of the lever 6, will operate as the pressure in the pressure-chamber is reduced to swing said lever about its fulcrum and through the rod 16 will swing the right-hand end of lever 8 downward, thereby swinging 100 the link 3 to the right and through the reach-rod *r* shortening the cut-off to the cylinder. As the speed of the engine falls the reverse action will take place—that is, the valve 24 will be partially closed and the pressure in 105 the pressure-chamber correspondingly increased, such increased pressure operating to depress the piston-rod 5, and thereby raise the right-hand end of the lever 8, and hence 110 lengthen the cut-off.

From the above description it will be seen that the governor in my engine has only to control the valve 24, and hence can be made extremely light, for as the type of valve which I prefer to use in my device is a balanced valve, such as shown, it will be evident that a very slight force is required to manipulate the same.

The reach-rod and connecting parts of the cut-off, which require considerable force to 120 operate, are positively operated by variations of pressure in the pressure-chamber.

In Fig. 2 I have illustrated a slightly-modified form of apparatus, and in this construction the valve-stem 20 is connected directly 125 to the governor *g* instead of being connected through the arms 17 and the lever 19, as in Fig. 1. In other respects the device of Fig. 2 is essentially the same as that in Fig. 1, the lever 6, however, being connected to the bell-crank 31, which in turn is connected to the reach-rod to the valve-gear.

If desirable, I may substitute for the bell-crank 31, Fig. 2, a lever similar to lever 8,

Fig. 1, which in turn operates the slotted link to control the cut-off.

Any suitable safety-valve 35 is employed in the pipe 13, so that should excessive pressure arise in the source of supply the safety-valve would relieve such pressure, and thereby prevent damage to the diaphragm.

As illustrated in Fig. 1, the slot in the link 3 is a double cam-slot, the purpose of this construction being to provide mechanism whereby should the belt *b*, for instance, break the mechanism herein illustrated would operate as a stop device to stop the engine and prevent damage.

15 The construction of the link is such that when the roll 10 is at either extremity of the slot the inlet-valves of the cylinder are closed, and when the roll 10 is central in the slot the cut-off is lengthened to its maximum extent.

20 As stated above, as the speed of the engine increases the right-hand end of the lever 8 is swung downward to thereby shorten the cut-off, and should the engine develop abnormal speed the operation will continue until the

25 roll 10 is at the lower extremity of the slot, in which case the inlet-valves will be closed. If, on the other hand, the belt *b*, which drives the governor, should break, the governor-arms will immediately fall and close the valve 24.

30 The maximum pressure would then be exerted on the diaphragm in the pressure-chamber, and the lever 8 would be turned until the roll 10 was at the upper extremity of the slot, in which case the inlet-valves would be closed again, and thereby stop the engine. I may also apply my invention to any steam-engine as a stop device, such device when used in this capacity being auxiliary to the ordinary means for controlling the speed of the engine.

35 40 When used as a stop device, I prefer to use the form of mechanism illustrated in Fig. 2, except that the valve-stem 20 would be connected to the governor by means of a flexible connection, such as the chain shown in dotted lines in said figure, and in this use of the apparatus the governor *g* would be connected up to the cut-off, so as to normally operate it in the ordinary way, and would also be connected to the valve-stem 20 by a flexible

45 means. With such a construction under normal conditions the governor *g* will control the speed of the engine in the ordinary way; but when abnormal or danger speed is developed for any reason the governor-arms will fly out sufficiently so as to take up the slack in the chain and raise the valve-stem 20, to thereby open the valve and reduce the pressure in the pressure-chamber *p*, such reduction of pressure operating to shorten the cut-off to a minimum, in which case the engine will take no

50 steam and of course stop.

55 It will be obvious that various changes can be made in the construction of the device without departing from my invention, which comprises a mechanism for controlling a steam-engine in which variations of steam-pressure in a pressure-chamber operate mechanism

which in turn controls the cut-off for the engine, such variations in pressure being controlled by the variations in the speed of the 70 engine, and I would consider as coming within my invention any device which embodies the above features.

I have herein illustrated my device in connection with a single-cylinder engine; but I 75 wish it understood that it may be applied equally as well to any multiple-cylinder engine.

Having fully described my invention, what I claim as new, and desire to secure by Letters 80 Patent, is—

1. In an engine-controller, a pressure-chamber, means connecting the same with the source of steam-supply for the engine, means governed by the speed of the engine to control the steam-pressure in said pressure-chamber, and means operated by variations in the steam-pressure in the said chamber to control the cut-off. 85

2. In an engine-controller, a cut-off for the 90 cylinder, a pressure-chamber, means connecting the same with the source of steam-supply for the cylinder, a ball-governor, means operated by said ball-governor to control the steam-pressure in the steam-chamber, and 95 means operated by variations in the pressure in said chamber to control said cut-off.

3. In an engine-controller, a pressure-chamber, a pipe connecting said chamber with the source of steam-supply for the engine, a movable member in said pressure-chamber operated by variations of steam-pressure therein, connections between said movable member and the cut-off, and means operated by the speed of the engine to control the steam-pressure in said pressure-chamber. 100 105

4. In an engine-controller, a cut-off for the cylinder, a pressure-chamber, a pipe connecting said chamber with the source of steam-supply for the cylinder, a diaphragm in said chamber, means connecting the diaphragm with the cut-off, whereby variations in steam-pressure in said chamber vary the cut-off, and means governed by the speed of the engine to control the pressure in said chamber. 110 115

5. In an engine-controller, a cut-off for the cylinder, a pressure-chamber, a pipe connecting said chamber with the source of steam-supply for the cylinder, a diaphragm in said chamber, means connecting the diaphragm with the cut-off whereby variations in steam-pressure in said chamber vary the cut-off, a centrifugal governor governed by the speed of the engine and means operated by said governor to control the pressure in said pressure-chamber. 120 125

6. In an engine-controller, a pressure-chamber, means for connecting the same with the source of steam-supply for the engine, a valve controlling the exhaust therefrom, means controlled by the speed of the engine for operating said valve, movable means in said chamber operated by variation in the steam-pressure therein, and mechanism connecting said

movable means with the cut-off of the engine, whereby the pressure in said chamber varies with the speed of the engine, and such variation operates to control the cut-off.

5. 7. In an engine-controller, a pressure-chamber, a pivoted link having a cam-slot, a reach-rod to the cut-off operated by said link, a lever engaging said cam-slot, means operated by variations in the pressure in said chamber 10 to operate said lever, and means controlled by the speed of the engine to vary the pressure in said pressure-chamber.

8. In an engine-controller, a pivoted link having a double cam-slot, a reach-rod connected to said link and controlling the cut-off, a pivoted lever having one end engaging the slot and controlling the position of the link, a pressure-chamber, mechanism controlled by the speed of the engine for varying the pressure 20 in said chamber, and means operated by the variations in the pressure in said chamber and connected to said lever, whereby such variations in pressure control the cut-off, the construction being such that whenever the 25 lever is at either extreme of the slot, the inlet-valves are closed.

9. In an engine-controller, a cut-off for the

cylinder, a piston-pot having a diaphragm therein, a pipe connecting said piston-pot with the source of steam-supply for the engine, a valve controlling the exhaust from said piston-pot, means controlled by the speed of the engine for operating said valve, a plunger connected to the diaphragm, a lever connected with the plunger, and connections between the lever and cut-off whereby variations in the pressure of the steam in the piston-pot control the cut-off.

10. In an engine-controller, a cut-off for the cylinder, a pressure-chamber connected with a source of steam-supply, said chamber having an outlet, a valve in said outlet, a centrifugal governor connected thereto whereby the speed of the engine controls the pressure in the pressure-chamber, and means operated 45 by variations of the pressure in said pressure-chamber to control said cut-off.

In testimony whereof I have signed my name to this specification in the presence of two subscribing witnesses.

RALPH J. PATTERSON.
